UNITED STATES PATENT OFFICE.

FRANK W. MERRICK, OF BOSTON, MASSACHUSETTS.

DESIGN FOR A SEWING-MACHINE NEEDLE.

SPECIFICATION forming part of Design No. 35,524, dated December 31, 1901.

Application filed December 1, 1899. Serial No. 738,918. Term of patent 14 years.

To all whom it may concern:

Be it known that I, FRANK W. MERRICK, a citizen of the United States, residing at Boston, in the county of Suffolk, State of Massachusetts, have invented a certain new and original Design for Sewing-Machine Needles, of which the following is a specification, reference being had therein to the accompanying drawings.

10 In the drawings, Figures 1 and 2 are elevations of a sewing-machine needle representing different sides thereof and showing my new design.

As shown in the drawings, the leading or 15 material features of my design consist of the straight stem 1, the diagonal notch 2, the diagonal groove 3, beginning on one side of the needle as a continuation of the notch 2 and

extending from the inner end of such notch on said side part way around the needle, and 20 the longitudinal groove 4 on the opposite side of the needle, extending from the inner end of the notch on such side toward the groove 3, the bottom of groove 3 lying deeper than the proximate portion in the line of the groove 4. 25

Having described my invention, what I claim as new, and desire to secure by Letters Patent, is—

The design for a sewing-machine needle, 30 as herein shown and described.

In testimony whereof I affix my signature in presence of two witnesses.

FRANK W. MERRICK.
